FRANK B. GRANGER, OF COLUMBUS, OHIO, ASSIGNOR TO HALL-BORCHERT DRESS FORM COMPANY, OF NEW YORK, N. Y., A CORPORATION OF NEW JERSEY.

ADJUSTABLE DRESS-FORM.

1,271,890.

Specification of Letters Patent.

Patented July 9, 1918.

Application filed October 28, 1916. Serial No. 128,336.

To all whom it may concern:

Be it known that I, FRANK B. GRANGER, a citizen of the United States, residing at Columbus, county of Franklin, State of Ohio, have invented an Improvement in Adjustable Dress-Forms, of which the following description, in connection with the accompanying drawing, is a specification, like characters on the drawing representing like parts.

This invention relates to adjustable dress forms of that type which comprise a plurality of sections adjustable relative to each other and connecting devices for connecting the adjacent sections and holding them in their relative adjusted positions. A type of dress form which is now commonly used is one in which the body portion has a shell-like formation and is divided into a plurality of sections which are connected to each other by fastening devices comprising a slotted strap secured at one end to one section and overlying an adjacent section and a clamping screw secured to the other section and extending through the slot of the strap and provided with a clamping nut which clamps the slotted strap in adjusted position. While a connecting device of this type will securely hold the various sections of the form in their adjusted position when the clamping nuts are all set up tight, yet the operation of making an adjustment in the position of any section involves first reaching into the interior of the form and loosening the various clamping nuts that hold the section in position, moving the section into its adjusted position, and then reaching into the form again and tightening up the clamping nuts on the various clamping screws. This operation is more or less laborious, and, moreover, if one or more of the clamping nuts are not properly tightened, the corresponding connecting device will not hold and the section of the form may be accidentally moved out of its correct position when the form is being used.

The object of my present invention is to provide an improved connecting device for connecting adjacent sections of a dress form, which device comprises a strap connected to one section of the form and a clamping device on the other section of the form which frictionally engages said strap with sufficient friction to hold the form sections in proper adjusted relation during any ordinary

use to which the dress form is subjected while permitting said sections to be adjusted relative to each other upon the application of sufficient force. With my improved connecting device the operation of adjusting any section of the dress form involves merely the act of moving said section into its proper adjusted position by applying sufficient force thereto, the frictional clamping device permitting this to be done but yet holding the section securely in place when it has once been adjusted.

In the preferred embodiment of my invention, I will provide my clamping device with a clamping screw and nut so that the connecting device may be securely locked in any adjusted position, but it is not necessary to use this clamping screw and nut during the ordinary use to which the dress form is subjected.

In order to give an understanding of my present invention I have illustrated in the drawings a selected embodiment thereof which will now be described, after which the novel features will be pointed out in the appended claims.

In the drawings, Figure 1 is a view of a body portion of a dress form having my improvements applied thereto;

Fig. 2 is a fragmentary view showing my connecting device looking from the interior of the form;

Fig. 3 is a section on the line 3—3, Fig. 2;

Fig. 4 is a section on the line 4—4, Fig. 2;

Fig. 5 is a perspective view of the frictional clamping device.

1 indicates generally a dress form which may be divided into sections in any suitable way. The form herein shown is divided horizontally across the waist at 2 and is divided vertically to present the hip sections 3, 4 and 5, and is also divided to present the shoulder sections 6 and the neck sections 7. This particular way of dividing the form, however, is not important so far as my invention is concerned, as my improved connecting device may be applied to dress forms divided in any other desirable way.

The sections of the dress form, however, the latter is divided, are connected by connecting devices, each of which comprises a strap 8 that is secured to one of the dress form sections and a frictional clamping device secured to another dress form sec-

tion and frictionally engaging the strap. In Figs. 2 and 3 the strap 8 is shown as fixedly secured at one end to the dress form section 4 by means of a suitable rivet 9, and said strap overlies the dress form section 5. The frictional clamping device which frictionally engages the strap is secured to the dress form section 5. This frictional clamping device is provided with two separated lips or ribs which engage one face of the strap and two arms which overlie and engage the opposite face of the strap between the lips or ribs and are so positioned that the strap is bent slightly between the ribs and is thus frictionally held in place. This clamping member is shown generally at 10 and it may conveniently be made or formed from a piece of sheet metal. The clamping member is formed with the two end portions 12, each of which is provided at its extremity with the upturned rib or lip 11. Said clamping member is also provided with the two arms 13 situated centrally between the ribs 11, which arms are bent over so as to embrace the edges of the strap 8. These arms are so situated relative to the ribs 11 that when the strap is passed beneath the arms and over the ribs 11, the arms 13 will cause the strap to be bent slightly between the ribs. The ends 12 of the clamping member may be made slightly resilient so that the pressure of the strap thereagainst will tend to bend them backwardly slightly as seen in Fig. 3. The clamping member is so constructed that the friction thereof against the strap 8 is sufficient to firmly hold the sections of the dress form in their adjusted position during any ordinary use to which the dress form is subjected. Any section, however, can be adjusted by applying thereto sufficient force to overcome the frictional resistance of the clamping member on the strap. The clamping member 10 may be secured to the dress form section in any suitable way. I have herein shown it as secured to a fastening plate 14 which in turn is secured to the dress form section 5 by rivets 15.

I have also provided herein means whereby the clamping member may be positively locked to the strap in case it is desired to positively lock the two dress form sections together. While in the ordinary use of the dress form, it may not be necessary thus to positively lock the sections together as the frictional clamping member will hold the sections in their adjusted position, yet under some circumstances, it may be desirable to positively lock the sections together so as to prevent absolutely any relative movement between them, and to accomplish this I have provided a clamping screw and clamping nut which cooperates with the clamping device to lock the fingers 13 against the strap thereby preventing the strap from sliding

through the clamping device. The fastening plate 14 has a clamping screw 16 secured thereto, said screw extending through an aperture in the clamping member 10 and being situated between the ends of the fingers 13. This clamping screw has a clamping nut 17 screwed thereto, which nut when screwed down may engage the fingers 13, thus clamping them against the strap 8 with sufficient pressure to lock the strap positively from movement. During the ordinary use of the dress form, the nut 17 will be backed off sufficiently so that it will have no binding action on the fingers 13, but when it is desired to lock the clamping member positively from adjustment, then the nut will be tightened against the fingers 13.

The strap 8 is provided with a longitudinal slot 18 through which the clamping screw 16 extends.

While I have illustrated herein a selected embodiment of my invention, I do not wish to be limited to the constructional features shown.

I claim:

1. A dress form divided to present a plurality of sections which are adjustable relative to each other, a strap secured to one section and a friction clamping member secured to an adjacent section and through which the strap slides, said clamping member being formed of a single piece of sheet metal bent to present two ribs extending transversely of one face of the strap at separated points, and two clamping fingers which engage the opposite face of the strap between said ribs and hold the strap yieldingly against the ribs.

2. A dress form divided to present a plurality of sections which are adjustable relative to each other, a strap secured to one section and a friction clamping member secured to an adjacent section and through which the strap slides, said clamping member including a curved resilient body portion having two ribs extending transversely of the strap and engaging one face thereof at separated points, and two clamping fingers which engage the opposite face of the strap between said ribs and hold said strap yieldingly against the ribs, said fingers being so disposed relative to the ribs that they cause a slight flexure in said body portion of the strap between the ribs.

3. A dress form divided to present a plurality of sections which are adjustable relative to each other, a strap secured to one section, a friction clamping member secured to an adjacent section and through which the strap slides, said clamping member having a resilient body portion presenting two ribs extending transversely of the strap and engaging one face thereof at separated points, and two clamping fingers which engage the opposite face of the strap and hold

the latter yieldingly against the ribs, and means for clamping said arms against the strap.

4. A dress form divided to present a plurality of sections which are adjustable relative to each other, a strap secured to one section, a friction clamping member secured to an adjacent section and through which the strap slides, said clamping member including a sheet metal body portion presenting two ribs extending transversely of the strap and engaging one face thereof at sep-

arated points, and two clamping fingers integral with said body which engage the opposite face of the strap and hold the latter yieldingly against the ribs, a clamping screw secured to said body portion, and a clamping nut on the screw adapted to engage said arms and by which the clamping pressure thereof against the strap can be varied. 15

In testimony whereof I have signed my name to this specification. 20
